UNITED STATES PATENT OFFICE.

EDWARD L. ACKERMAN, OF DETROIT, MICHIGAN, ASSIGNOR TO JOSEPH N. SMITH & COMPANY, OF DETROIT, MICHIGAN, A CORPORATION OF MICHIGAN.

AUTOMOBILE-HOOD HINGE.

Application filed May 9, 1921. Serial No. 468,081.

To all whom it may concern:

Be it known that I, EDWARD L. ACKERMAN, a citizen of the United States, residing at Detroit, county of Wayne, State of Michigan, have invented a certain new and useful Improvement in Automobile-Hood Hinges, and declare the following to be a full, clear, and exact description of the same, such as will enable others skilled in the art to which it pertains to make and use the same, reference being had to the accompanying drawings, which form a part of this specification.

This invention relates to hinges for automobile hoods and the object of the invention is to provide a concealed hinge for the automobile hood members whereby the said members have a symmetrical outer surface which is both pleasing in appearance and easily cleaned. A further object of the invention is to provide a concealed hood hinge in which the two hood members are each hinged separately to a supporting member, the edges of the hood members being normally in contiguous relation with a central rib or raised portion of the supporting member when the hood is closed. A still further object of the invention is to provide a concealed hood hinge in which one of the hood members may be swung upwardly and supported in position without contacting other portions of the hood or said central portion. A novel feature of the invention is involved in the construction whereby the usual unsightly hood hinge is eliminated and also in the construction whereby either hood member is prevented from coming in contact with other portions of the hood thus preventing marking and disfiguring of the enamel thereon. These objects and the several novel features of the invention are hereinafter more fully described and claimed and the preferred form of construction by which these objects are attained is shown in the accompanying drawings in which—

Fig. 1 is a plan view of a portion of an automobile hood partly broken away to show the hinge construction embodying my invention.

Fig. 2 is a section taken on line 2—2 of Fig. 1.

Fig. 3 is a section similar to Fig. 2 showing an alternative form of construction.

Fig. 4 is a section taken on line 4—4 of Fig. 3.

As shown more particularly in Fig. 2 the device consists of a supporting member 1 which is provided with a channel 2 on each side thereof and is also provided with a central rib or raised portion 3 having a flat outer surface adapted to form part of the hood surface when the hood is closed. The supporting member 1 is provided with side flanges 4 which extend upwardly and are each provided with an inturned flange 5. Each flange 5 is provided with knuckles 6 shown more particularly in Fig. 1 which extend about and support a hinge pintle 7 shown in Figs. 1 and 2. The hood is provided with a pair of sheet metal hood members 8 which are each provided with a return bent portion 9 the said portions 9 being formed at the inner edge with extending portions 10, shown more particularly in Fig. 1, which also extend about the hinge pintles 7. By this construction the hood members 8 are each provided with an edge 11 which when the hood is closed are brought to contiguous relation with the edges of the rib portion 3, as shown in Figs. 1 and 2. By this construction the hood members 8 may be swung upwardly on the hinge pintles 7 and when so turned the members 8 take the position shown in dotted lines in Fig. 2. The supporting member 1 is so formed that upon turning the member 8 to the upper position the edge 11 thereof contacts the inner face of the portion 4 before the outer face of the member 8 strikes the edge of the portion 3 of the supporting member. Thus the members 8 are prevented from contacting any other portion of the hood which prevents marring of the enamel thereon the liability of denting the surface of the hood member.

In Fig. 3 I have illustrated an alternative form of the device. In this case the channel 2 is formed with an upwardly extending wall 12. In this case a separate hinge is provided consisting of a leaf 13, pintle 14 and a leaf 15 which is provided with a depending portion 16 as shown, which is riveted or welded to the wall 12 of the supporting member. To secure the hood member 8 to the hinge the hood member is provided with a return bent portion 17 which extends about the leaf 13 of the hinge and may be welded or secured thereto in any suitable manner. As shown in Fig. 4 the leaf 13 is provided with knuckles 18 ex-

tending about the pintle 14 and the leaf 15 is provided with knuckles 19 also extending about the pintle 14. The operation of this construction is the same as before described, the hood member 8 being swung upwardly on the pintle 14 as a center of rotation until the edge 20 of the hood member 8 engages the inner face of the wall 12 at which time the member 8, as shown more particularly in dotted lines in Fig. 3, is supported in position without contacting the edge of the rib portion 3 of the supporting member 1. By this construction a hood of very neat appearance is provided in which the usual protruding hood hinge is eliminated, the hinges for the hood members being concealed beneath the hood.

From the foregoing description it becomes evident that the device is exceedingly simple and efficient in operation, of comparatively low manufacturing cost, providing a hinge construction of very neat outer appearance having several advantages over the normal construction and provides a device which accomplishes the objects desired.

Having thus fully described my invention, its utility and mode of operation, what I claim and desire to secure by Letters Patent of the United States is—

1. In an automobile hood, a supporting member having a central rib portion and a substantially U shaped channel portion on each side thereof, each channel portion having an inwardly turned flange on the outer side thereof, a pintle carried by each flange,

a hood member pivotally mounted on each pintle, the edge of either of the hood members when swung to the upper position engaging a side of the channel portion in a manner to prevent contact with the other portions of the hood.

2. In an automobile hood, the combination with the two hood parts, of a central supporting member, a hinge for each hood part having one leaf thereof attached to the respective side of the central member, the edge of the respective side of the central member, the edge of the respective hood part being bent over and secured to the other leaf of its hinge positioning the axis of the hinge at a distance from the edge of its hood member and on the under side thereof.

3. In an automobile hood, the combination with the two hood parts, of a central supporting member having channels extending longitudinally on each side thereof with the terminal edge inturned over the channel, a pintle carried by each inturned flange, a hood member pivotally mounted on its pintle, the edge of the hood members being return bent to engage the hinge at a distance from the edge of the hood and channel being of a depth to permit the edges of the hood members to be turned downward thereinto to engage a wall of the channel preventing contact with the other portions of the hood.

In testimony whereof, I sign this specification.

EDWARD L. ACKERMAN.
